SHOE STRETCHING LAST

Patsy La Marca, Coraopolis, and Quirino D. Romito, Charlerol, Pa.

Application October 30, 1933, Serial No. 695,764

11 Claims. (Cl. 12—128.3)

This invention relates to a combination adjustable shoe tree and shoe-stretching last and has for its primary object the provision of an improved device of this character which is adapted to be effectively used for selectively stretching any part of a shoe, slipper, or similar piece of footwear, or as a shoe tree to retain various sizes of footgear in shape when not in use.

Another object is to provide a last of this type which is simple and sturdy of construction, dependable in operation, and which may be readily adjusted to either stretch the various parts of a shoe, to relieve the user of any irritating pressure, or uniformly adjusted to function as a properly shaped tree for different sizes of footgear.

A further and more particular object is to provide a last which is made up entirely of parts which may be adjusted either independently or substantially uniformly to provide either selective sectional stretching or uniform enlargement.

These and various other objects as well as the various other novel features and advantages of the invention will be apparent when the following detailed description is read in conjunction with the accompanying drawings of which Fig. 1 is a plan view of one embodiment of the invention; Fig. 2 a side view partly in elevation, and partly in section, of the last shown in Fig. 1; Fig. 3 a sectional view of the toe portion thereof, showing a detachable seam-stretching shield mounted on the top of it; Fig. 4 a perspective view of the stretching shield shown in Fig. 3; Fig. 5 an exploded view partly in plan and partly in section of the last shown in Fig. 1; Fig. 6 a vertical section taken on the line VI—VI of Fig. 1; Fig. 7 a side view of one of the detachable side plates used on the sides of the last as shown in Fig. 1; Fig. 8 a view similar to Fig. 7 of a detachable bunion plug; Fig. 9 a vertical section taken through another embodiment of the invention; Fig. 10 a plan view of the heel portion of the latter embodiment showing the adjusting screws for the front part of the last removed; and Fig. 11, a vertical section taken on the line XI—XI of Fig. 9.

Referring in detail to the drawings and first more particularly to Figs. 1, 2, 5 and 6, the numeral 1 designates a skeleton-like frame on which the various movable parts of the last are supported. As shown best in Fig. 5 this frame comprises the center structure of the last being provided with a base the surface of which extends from the heel to the toe, and has a contour similar to the bottom of the human foot. At its rear end there is secured a vertical wall 2 which forms a partition between the heel and forward part

of the last and functions as a support for a number of adjusting screws as will presently appear.

In front of the dividing wall 2 the frame 1 is similar to a U-shaped channel and is equipped at its forward end with a double end wall structure 3 which is adapted to form a pocket 4 for receiving a depending tongue 5 on a detachable toe section 6 which is secured to and forms the front end of the last, such toe being provided in different sizes to accommodate different sizes of shoes and to form a uniform shape when the last is adjusted to different sizes.

The side walls of the last are made up of laterally expandable instep and joint sections 7 and 8 which may be cast substantially solid as shown or made in the form of shells out of any suitable material. These, as shown, are arranged to fit against the sides of the frame 1 when adjusted to their inner position and have outer walls approximating in shape as nearly as possible the contour of the instep and front joint portion of the foot. For adjusting such sections two pairs of screws 9 and 11 are mounted in the frame 1 in spaced relation to each other and threadably engaged in threaded openings 12 and 13 provided in sections 7 and 8 for their reception. At their inner ends these screws are rigidly supported in the frame 1 and equipped with miter gears 14 and 15 which are meshed with bevelled pinions 16 and 17 respectively. These pinions in turn are mounted on the lower ends of a pair of screw shafts 18 and 19 which are extended through openings 21 and 22 respectively in the back wall 2 of the frame 1, to a convenient point above the top of the heel of the last.

In order that the sections 7 and 8 will be actuated in opposite directions when the screws 18 and 19 are turned, the screws 9 and 11 are provided with reverse threads, and to insure their moving in proper alignment as well as to hold them in place at all times, a pair of guide pins 23 and 24 is secured to the sides of the frame 1 in a manner to engage holes 25 and 26 formed in such sections. To further assist in guiding the movement of these parts a pair of U-shaped guides 27 is secured to the opposite sides of the frame 1 at the junction of the two side sections 7 and 8 being disposed to fit in lateral slots cut in the adjacent edges of the side sections.

Over the top of the instep of the last there is provided a tongue-like cover plate 28 which is connected at its lower end by a hinge 29 to the frame 1 adjacent the point where the toe tip is connected to the frame. At the upper end of such tongue-shaped cover a slot 31 is provided, and

through it an adjusting screw 32 is projected, such screw being connected by a ball and socket joint 33 to the upper edge of the division wall 2. To provide for raising and lowering the upper end 5 of the tongue-shaped cover plate 28 a threaded block 34 is mounted on the screw to slidably engage the slot 31.

In this particular embodiment of the invention, which is intended more especially for use 10 with ladies' shoes, although not necessarily so limited, the heel proper of the last is made up of a single hollow heel piece 35 which is adjustably mounted on a guide shaft 36 connected to the rear face of the division wall 2 of the frame 1. Like 15 the toe section 6, this heel section may be made in different interchangeable sizes to accommodate different sizes of shoes. In it a hole 37 is provided for the reception of the shaft 36, and for effecting its adjustment a screw 38 is provided, 20 which as shown is secured at its forward end to a miter gear 41 mounted on the right side of the frame 1 near the division wall 2. The rear end of such screw is extended through an opening 42 in the wall 2 and into the heel section 35. To cause 25 the heel to move when the screw 38 is turned, a nut 43 is mounted against turning between a pair of spaced bosses 44 and 45 in which holes 46 and 47 are provided for the passage of the screws. In order to allow the heel to adapt itself to fit shoes 30 having differently inclined soles or heights of heels, these holes 46 and 47 are made sufficiently larger than the screw to permit the heel to teeter about the bosses when it is loosened from the wall 2 as shown by the dotted line in Fig. 2.

35 For actuating the screw 38 a bevel pinion 48 mounted on a screw shaft 49 is meshed with the miter gear 41, the shaft 49 being passed through a hole 51 in the back wall 2 of the frame 1 and conveniently arranged with the other screw 40 shafts 18, 19 and 32, above the upper end of the heel, such shafts all being provided with non-circular ends for the reception of a common turning tool not shown by which they are adjusted.

As will be appreciated, from the foregoing description, a last constructed in this fashion can 45 be readily elongated or shortened by turning the heel-adjusting screw shaft 49, the instep side sections 7 expanded or contracted by turning and adjusting screw 18, and the joint sections 8 adjusted by turning the screw shaft 19. The tongue-shaped cover plate 28 may be also adjusted by either elevating the shaft 32 which 50 lifts such cover to some extent when it is elevated, or by turning the shaft to move the slide block 55 34 in the slot 31.

To make the toe of the last correspond in size 60 with the different adjustments of the rest of the last, the toe tip 6 as previously indicated may be changed, as also may be the heel section 35. To further enlarge the last, particularly for stretching 65 shoes which are partly broken in, or for locally stretching the lower edges of a shoe as well as for uniformly spreading the pressure exerted on the shoe when one or the other of the sections 7 or 8 is adjusted, adjustable side plates 53 and 54 are provided. To adapt these to fit 70 the last they are curved in the shape of the last so that they fit smoothly over that portion of the last which they are adapted to cover. For holding such plates in place pins 55 are provided in spaced relation on their inner walls to fit in holes 56 and 57 formed in the side wall sections 7 and 8. As will be appreciated, such plates may be used either singly or in pairs.

75 To relieve the pressure on a bunion a bunion

5 plug 58 is provided, being equipped with a pin 59 adapted to fit in one of the holes 57 in the joint section of the last. This plug, of course, may be provided in various shapes to accommodate different affected areas, although only one 5 is shown.

To adapt the last for use in sizes of shoes which are larger than can be accommodated by the full adjustment of the screw 38 an auxiliary heel section 61 is provided. This section is similar in 10 shape to the back end of the heel and is equipped with pins 62 for attaching it to the rear end of the heel section 35, holes 63 being drilled in the section 35 for their reception.

To provide for exerting a greater pressure over 15 the front joint section of a shoe than can normally be exerted by the tongue plate 28, a detachable toe plate 64 is provided which may be used as may be the other auxiliary parts of the last at the will of the operator. As shown in 20 Figs. 1 and 2 this plate is adapted to fit over the forward end of the tongue cover 28 and the rear end of the toe tip 6, and is equipped with pins 65 which are arranged to fit in holes 66 and 67 provided in the toe section 6 and the plate 28 25 respectively.

For stretching the seam of a shoe over the forward joint of the foot a detachable seam-stretching shield 68 is provided, being adapted to fit on the cover plate 28 and to engage such portion of the shoe. For holding it in place it is provided with a lug 69 which is arranged to fit in a slot 71 cut in the cover plate 28. Such shield, as shown, is inclined upwardly at a rather steep angle to adapt it to effectively stretch the seam 35 portion of the shoe with but slight elevation of the tongue cover plate 28.

Referring to Figs. 9, 10 and 11, an embodiment of the invention is shown which is more especially devised for use with men's shoes, and differing 40 from the above-described embodiment primarily only in the construction of its heel portion and in the contour of the bottom of the last. To avoid repetition, the description of the forward part of this last, which is the same as the last 45 previously described, is omitted, but to distinguish the two, the suffix *a* has been added to the reference characters applied to the various parts.

As illustrated, the heel structure of this latter embodiment of the invention comprises a body 50 section 72 which forms the bottom portion of the heel and on which the other parts of the heel are mounted, being itself mounted on a slide rod 36a attached to the back wall 2a of the frame 1a and an adjusting screw 38a in practically the same way as the heel section 35 is mounted, differing, however, from the previous structure in that the heel is not adapted to teeter on the screw 38a. For men's shoes, the pitch of the insole does not vary sufficiently to require 60 any teetering action of the heel for the last to fit different sizes of shoes properly.

Secured by adjusting screws 74 to the sides of body section 72 of the heel is a pair of adjustable counter-sections 75 which may be expanded or contracted to fit various sized shoes. These screws 74 like the other adjusting screws of the last are provided with reverse threads and mounted at their inner ends in brackets 76 70 formed on the top of the body section 72. For adjusting such screw, miter gears 77 are secured to them between the bosses 76 and meshed with a miter pinion 78 which is attached to a screw shaft 79 extended to the top of the heel and pro- 75

vided with a non-circular end for effecting its adjustment.

To make the back of the heel correspond in shape with the counter-sections when they are adjusted, a detachable heel tip 81 is mounted on the back of the heel and adapted to be replaced by tips of such different sizes as may be required. For holding the tip in place it has a pair of pins 82 secured to it which are arranged to fit in holes 83 provided in the rear face of the heel body section 72 for their reception. With this construction, as will be appreciated, the heel as well as the forward part of the last can be expanded and contracted laterally as well as endwise which is particularly desirable when used with men's shoes.

According to the provisions of the patent statutes, we have explained the principle and mode of operation of our invention and have illustrated and described what I now consider to represent its best embodiment. However, we desire to have it understood that, within the scope of the appended claims, the invention may be practiced otherwise than as specifically illustrated and described.

We claim:

1. A combination adjustable shoe tree and shoe-stretching last, comprising a supporting frame, a pair of uniformly laterally expansible side sections adjustably mounted on opposite sides of said frame to form the instep and forward joint portions of the last, a detachable toe section secured to the front end of said frame, a tongue-shaped instep cover plate pivotally connected at one end to said frame at its forward end, a cross wall secured to the rear end of said frame, an axially adjustable heel section pivotally secured to said cross wall and individual means for adjusting said heel section, said oppositely disposed instep sections, said oppositely disposed joint sections, and the upper end of said instep cover plate.

2. A combination adjustable shoe tree and shoe-stretching last, comprising a supporting frame, a pair of uniformly laterally expansible side sections extending from the top to a point adjacent the center line of the bottom of the last and adjustably mounted on opposite sides of said frame to form the instep and forward joint portions of the last, a detachable toe section secured to the front end of said frame, a tongue-shaped instep cover plate pivotally connected at one end to said frame at its forward end and extending upwardly over the adjacent edges of said oppositely disposed side sections, a cross wall secured to the rear end of said frame, a heel section connected for axial adjustment to said cross wall, and independent means for adjusting said heel section, said oppositely disposed instep sections, and said oppositely disposed joint sections.

3. A combination adjustable shoe tree and shoe-stretching last, comprising a supporting frame forming the center portion of the bottom of said last, a pair of uniformly laterally expansible side sections adjustably mounted on opposite sides of said frame to form the instep and forward joint portions of the last, a detachable toe section secured to the front end of said frame, a tongue-shaped instep cover plate pivotally connected at the lower end to the forward end of said frame, a cross wall secured to the rear end of said frame, a heel section pivotally and axially adjustably connected to said cross wall, and independent means supported in said cross wall for adjusting said heel section, said oppositely disposed instep

sections, said oppositely disposed joint sections, and the upper end of said instep cover plate.

4. A combination adjustable shoe tree and shoe-stretching last, comprising a supporting frame having a cross section of channel shape, a pair of uniformly expansible side sections adjustably mounted on opposite sides of said frame to form the instep and forward joint portions of the last, a detachable toe section secured to the front end of said frame, a tongue-shaped instep cover plate pivotally connected at its lower end to the forward end of said frame, a cross wall secured to the rear end of said frame, a heel section pivotally and axially adjustably connected to said cross wall, oppositely disposed screws secured in the sides of said frame and engaged in threaded openings in said instep and joint sections, gear means mounted in the channel portion of said frame and secured to said screws, adjusting pinions arranged to engage said gears and mounted on adjusting shafts supported in said cross wall for separate operation, a screw mounted in said frame for adjusting said heel section, and a screw-shaft equipped with means for adjusting said heel section.

5. A combination adjustable shoe tree and shoe-stretching last, comprising a supporting frame, a pair of uniformly expansible side sections extending from the top to a point adjacent the bottom center line of said last mounted on opposite sides of said frame to form the instep and forward joint portions of the last, a detachable toe section secured to the front end of said frame, a tongue-shaped instep cover plate pivotally connected at its lower end to the forward end of said frame, a cross wall secured to the rear end of said frame, an axially adjustable heel section removably connected to said cross wall, a pair of laterally adjustable counter-members mounted on the sides of said heel section, and separate means for axially adjusting said heel section, laterally adjusting said counter-sections, laterally adjusting said oppositely disposed instep sections, laterally adjusting said oppositely disposed joint sections, and elevating the upper end of said instep cover plate.

6. A combination adjustable shoe tree and shoe-stretching last, comprising a supporting frame, a pair of uniformly laterally expansible side sections adjustably mounted on opposite sides of said frame to form the instep and forward joint portions of the last, an expansion plate adapted to extend over the junction of said side sections detachably connected thereto, a detachable toe section secured to the front end of said frame, a tongue-shaped instep cover plate pivotally connected at one end to said frame at its forward end, a cross wall secured to the rear end of said frame, an axially adjustable heel section pivotally secured to said cross wall and individual means for adjusting said heel section, said oppositely disposed instep sections, said oppositely disposed joint sections, and the upper end of said instep cover plate.

7. A combination adjustable shoe tree and shoe-stretching last, comprising a supporting frame, a pair of uniformly laterally expansible side sections extending from the top to a point adjacent the center line of the bottom of the last and adjustably mounted on opposite sides of said frame, a detachable toe section secured to the front end of said frame, a tongue-shaped instep cover plate pivotally connected at one end to said frame at its forward end and extending upwardly over the adjacent edges of said oppositely dis-

posed side sections, a stretching plate detachably mounted with its ends engaging said toe section and said instep cover plate and adapted to extend over the area affected by the adjustment of said latter plate, a cross wall secured to the rear end of said frame, a heel section connected for axial adjustment to said cross wall, and independent means for adjusting said heel section, said oppositely disposed instep sections, and said oppositely disposed joint sections.

10. 8. A combination adjustable shoe tree and shoe-stretching last, comprising a supporting frame forming the center portion of the bottom of said last, a pair of uniformly laterally expandable side sections adjustably mounted on opposite sides of said frame to form the instep and forward joint portions of the last, an expansion plate detachably mounted on the side of said last with its ends engaging both said instep and joint section,

15. a detachable toe section secured to the front end of said frame, a tongue-shaped instep cover plate pivotally connected at the lower end to the forward end of said frame, a detachable stretching plate mounted on the lower end of said instep cover plate with one end extended over said toe section, a cross wall secured to the rear end of said frame, a heel section axially adjustably connected to said cross wall, and independent means supported in said cross wall for adjusting said heel section, said oppositely disposed instep sections, said oppositely disposed joint sections, and the upper end of said instep cover plate.

20. 9. A combination adjustable shoe tree and shoe-stretching last, comprising a supporting frame, a pair of uniformly expandable side sections adjustably mounted on opposite sides of said frame to form the instep and forward joint portions of the last, a detachable toe section secured to the front end of said frame, a tongue-shaped instep cover plate pivotally connected at its lower end to the forward end of said frame, a

25. cross wall secured to the rear end of said frame, a main heel section axially adjustably connected to said cross wall, an auxiliary heel section detachably mounted on the rear end of said main heel section, oppositely disposed screws secured in the sides of said frame and engaged in threaded openings in said instep and joint sections, a gear mounted on the inner end of each of said screws, adjusting pinions arranged to engage said gears and mounted on adjusting shafts supported in 10 said cross wall for separate operation, a screw mounted in said frame for adjusting said heel section, and a screw shaft equipped with means for adjusting said heel section.

30. 10. A combination adjustable shoe tree and shoe-stretching last, comprising a supporting frame, a pair of uniformly expandable side sections extending from the top to a point adjacent the bottom center line of said last mounted on opposite sides of said frame to form the instep and forward joint portions of the last, a detachable toe section secured to the front end of said frame, a tongue-shaped instep cover plate pivotally connected at its lower end to the forward end 20 of said frame, a shield for stretching the seam at the top of the joint section of a shoe detachably mounted on the lower end of said instep cover plate, a cross wall secured to the rear end of said frame, an axially adjustable heel section removably connected to said cross wall, and separate 25 means for axially adjusting said heel section, laterally adjusting said oppositely disposed instep sections, laterally adjusting said oppositely disposed joint sections, and elevating the upper end 30 of said instep cover plate.

35. 11. A stretching last according to claim 1 having a bunion plug detachably mounted on the side of one of said side joint sections.

PATSY LA MARCA.
QUIRINO D. ROMITO.
